UNITED STATES PATENT OFFICE.

ELIHU THOMSON, OF SWAMPSCOTT, MASSACHUSETTS, ASSIGNOR TO GENERAL ELECTRIC COMPANY, A CORPORATION OF NEW YORK.

STEAM-POWER SYSTEM.

1,063,619.

Specification of Letters Patent.

Patented June 3, 1913.

Application filed July 30, 1908. Serial No. 446,084.

To all whom it may concern:

Be it known that I, ELIHU THOMSON, a citizen of the United States, residing at Swampscott, county of Essex, State of Massachusetts, have invented certain new and useful Improvements in Steam-Power Systems, of which the following is a specification.

This invention relates to means for generating elastic fluid vapor for power purposes, and especially to steam boilers and their controlling devices for automobile vehicles.

For driving large trucks used for heavy haulage it is quite customary to employ steam engines, and as these vehicles run at low speeds and in a comparatively smooth and steady manner, it is possible to fire the boiler with solid fuel, such as coal or coke, instead of with gasoline, oil or other liquid hydrocarbon. The objection to solid fuel is that when the consumption of steam ceases there is apt to be a blowing off of steam at the safety valve owing to the continued heating of the boiler by the bed of burning fuel. Furthermore, if the boiler be of the flash or coil type, and is exposed directly to the fire, the shutting down of the steam consumption will cause the water to be driven out of the tubes, so that they are liable to overheat.

My invention aims to obviate these difficulties by locating the fire and the boiler in separate communicating chambers, with means for restricting or closing the communication between them so that the fire can no longer heat the boiler when it is desired to check the generation of steam. The restriction or closure may be made manually or automatically as desired. Means may also be provided for shutting off the air supply from the fire when the fire box is shut off from the boiler, and for so connecting the steam valve of the engine with either or both of said means so that they can be operated simultaneously therewith when the engine is shut down by closing the valve. By thoroughly jacketing the fire box with a good non-conductor of heat the fire will remain alight for many hours and ready at any time to be brought into service by letting in air and opening up communication with the boiler.

The accompanying drawings illustrate

diagrammatically an embodiment of my invention, Figure 1 being a sectional elevation of a complete system, Fig. 2 showing a modification of the fire-box and boiler, and Fig. 3 being a sectional elevation of said system showing a modification of the controlling levers.

The boiler 1, Figs. 1, or 33, Fig. 2, is represented as a coil or flash boiler, but this is simply illustrative, as it may be of any desired type. In any case it is inclosed in a jacket 2, Fig. 1, or 34, Fig. 2, of heat refracting material, provided with a flue or chimney 3, Fig. 1, or 35, Fig. 2, for the escape of hot gases, said flue being preferably directed downward, as shown. The boiler chamber 76 may also have an opening at the top closed by a lid 4, Fig. 1, or 36, Fig. 2, which can be removed when starting the fire in order to give a good natural draft. The fire-box 5, Fig. 1, or 37, Fig. 2, also, is lined with a good non-conductor of heat. It contains a grate 6, Fig. 1, or 38, Fig. 2, of any suitable construction to support the coal, coke or other solid fuel 7, Fig. 1, or 39, Fig. 2, which may be fed in either by hand from time to time through an opening closed by a lid 8, Fig. 1, or door 8', Fig. 2, or automatically by any well-known mechanism, as will be readily understood.

Between the fire-box and the boiler chamber is a passageway which can be controlled so as to prevent the hot gases from exerting an undue heating effect upon the boiler. In Figs. 1 and 3 this passageway can be entirely or partially closed by a damper or valve 9, preferably arranged to slide, and capable of operation by suitable mechanism, such as the lever 10 and rocker-arm 11 engaging with a connecting rod 12 pivoted to said damper. The lever is rendered adjustable by a latch 13 and a notched quadrant 14, or other equivalent device. In order to control the supply of air to the ash-pit, a door 15, Figs. 1 and 3 or 40, Fig. 2, is provided, and if desired it may be operated by the lever 10 through a second rocker-arm 16 and connecting-rod 17. By slotting the rod 12, the lever can be manipulated to regulate the door after the damper 9 has been shut, in order to govern the fire while it is shut off from the boiler.

Fig. 2 shows a construction by means of which, instead of employing a damper or

2
5 valve to cut off the communication between the fire-box and the boiler-chamber, the same or a similar effect can be produced by simply restricting the passageway between the fire and the boiler, as shown at 18. 10 This passageway is so small that the radiation from the glowing fuel is not sufficient to overheat the boiler when steam consumption ceases, especially when the draft of air to the fire is checked by a damper in the ash-pit or in the flue or chimney leading from the boiler chamber. The size of the passageway and the control of the draft may be so regulated as to permit a small 15 leakage of heat to the boiler chamber, just sufficient to maintain the proper temperature of the boiler, and therefore have it ready for sudden duty at any time. If desired, the passageway may be subdivided in any suitable manner, so as to distribute the flow of 20 hot gases when the fire is under draft. Such a subdivision may be conveniently effected by the deflector or baffle-plate 19 located in the boiler chamber just above the passageway 18, which plate also checks radiation of 25 heat from the fire to the boiler when the draft is cut off while the engine is shut down.

In order to illustrate a complete power system, I have shown the boiler in Figs. 1 30 and 3 connected by a pipe 20 with an engine 21, the admission of steam to the cylinder being controlled by a throttle valve 22. The engine exhausts into a condenser 23 from 35 which the water of condensation drains into the water-tank 24, which supplies the boiler through a steam pump 25 or other equivalent water-feeding device. The exhaust steam from the pump, and also any steam 40 which passes through the condenser flows to an ejector 26, Figs. 1 and 3 or 41, Fig. 2, located in the down-draft flue 3 or 35 respectively for producing a draft on the fire when the engine is running.

45 It is desirable to interconnect the mechanism for controlling the damper and door and that for operating the throttle valve of the engine, so that when the steam is cut off the fire will also be checked or shut off 50 from the boiler. An arrangement for effecting this is shown in Fig. 3. A sector gear 27 is secured to the stem of the throttle valve 22 and meshes with a rack 28 sliding in guides 29. A rod 30 is pivoted to the 55 rack and is provided with a plurality of notches 31 adapted to engage with a pin 32 on the lever 10. When the lever 10 is moved to shut the damper 9 and door 15, the steam will be shut off also. The notches 31 enable 60 the relative closing points of the damper and door and the throttle to be adjusted.

65 Since there is no blowing of steam through an exhaust pipe or at a safety-valve, and no overheating of the boiler when steam is not being used, this system is especially adapted

to trucks for use in city streets. But it is also applicable to railway vehicles, and even to stationary plants, being readily capable of automatic regulation for variations in speed or load, in ways which will be evident 70 to the skilled engineer.

What I claim as new and desire to secure by Letters Patent of the United States, is,

1. The combination with a generator for supplying motive fluid to a prime mover, 75 of a chamber containing said generator, a fire-box in which fuel is burned to supply heat to the generator, a passage connecting the fire-box with the chamber to deliver heat to the latter, means arranged in the passage 80 for checking the radiation of heat from the fire-box to the chamber to check the generation of motive fluid when the prime mover is shut down, a device for shutting off the admission of air to the fire-box so that in co-operation with said means combustion and loss of heat by radiation will be substantially prevented, valve means for regulating the admission of motive fluid to the prime mover, and means for simultaneously closing 85 the valve and said device.

2. The combination with a boiler for supplying steam to an engine, of a chamber in which the boiler is located, a fire-box in which fuel is burned to supply heat to the 95 boiler, a conduit between the fire-box and the chamber, means for confining the heat of the fire to the fire-box and checking combustion when the engine is shut down, comprising a non-conducting lining for the walls 100 of the fire-box, means for shutting off the admission of air to the fire-box, and a device arranged in said conduit for checking the radiation of heat from the fire-box to the boiler, a valve for regulating the admission 105 of steam to the engine, and mechanism for simultaneously opening and closing the valve and said means for shutting off the admission of air to the fire-box.

3. The combination with a generator for 110 supplying elastic fluid vapor to a prime mover, of a chamber containing said generator, a fire-box for heating the generator which is arranged separate from said chamber but in communication therewith and 115 means including devices arranged adjacent to the inlet and outlet of the fire-box for simultaneously shutting off the heat from the chamber to check the generation of vapor and the entrance of air to the fire-box 120 to arrest combustion therein when the prime mover is shut down.

4. The combination with a generator for 125 supplying elastic fluid vapor to a prime mover, of a chamber containing said generator, a separately arranged fire-box, a grate for solid fuel in said fire-box, a damper between the fire-box and the chamber, a door for regulating the supply of air to the fire-box, and means for operating said damper 130

and door to simultaneously shut off the heat of the fire from the generator and check the entrance of air in the fire-box.

5. The combination with a generator for supplying elastic fluid to a prime mover, of a chamber containing the generator, a fire-box separate from the chamber, a grate for solid fuel arranged in said fire-box, a conduit for conveying gases heated by the combustion of the fuel from the fire-box to the chamber to heat the generator during its normal operation, a damper in the conduit, a door for controlling the supply of air to the fire, means connecting the damper and the door, and a device for actuating said means to shut off the heat from the chamber to check the generation of fluid and arrest combustion in the fire-box when the prime mover is shut down.
- 10 6. The combination with a prime mover and a generator for supplying elastic fluid to the prime mover, of a chamber containing the generator, a fire-box separate from the chamber, a grate for solid fuel arranged 15 in said fire-box, a conduit for conveying the gases heated by the combustion of the fuel from the fire-box to the chamber to heat the generator during its normal operation, a damper in the conduit, a door for controlling the supply of air to the fire, a device for regulating the supply of elastic fluid

to the prime mover, mechanism connecting the damper and the door with said device, and means for operating said device which acts through said mechanism to move the 35 damper and the door to shut off the heat from the chamber to check the generation of fluid, and to arrest combustion in the fire-box when said device is operated to cut off the supply of fluid to the prime mover. 40

7. The combination with an engine and a generator for supplying steam to said engine, of a chamber containing the generator, a fire-box separate from the chamber, a grate for solid fuel arranged in the fire-box, a 45 conduit for conveying the gases generated and heated by the combustion of the fuel from the fire-box to the chamber to heat the generator during its normal operation, a damper in the conduit, a valve for controlling the supply of steam to the engine, a connection between the valve and the damper, and means acting through said connection to simultaneously close the valve and the damper. 50

In witness whereof, I have hereunto set my hand this 28th day of July, 1908.

ELIHU THOMSON.
